described to point out their manner of organization, after which the operation of the complete machine will be set forth in connection with the circuit diagram, at which time the coordination 5 of the various units will be set forth. The main 10 drive shaft of the machine is indicated at 10 in Fig. 1 and may be driven by any suitable source of power to maintain it in constant rotation. The shaft 10 carries a gear 21 which meshes with and 15 drives a gear 20 freely mounted on the card feed shaft F. Secured to gear 20 is a clutch driving element 19 which is consequently in constant motion. Lying in the plane of clutch element 19 is a spring-pressed dog 18 which is carried by and 20 pivoted to a cam 22. An armature latch 17 normally holds the pawl 18 out of engagement with the driving element 19. Upon energization of magnet 16, latch 17 is rocked counterclockwise to release pawl 18 whereupon a spring will move it into engagement with the driving element 19 to cause rotation of cam 22.

The cam 22 is secured to shaft F so that the shaft will rotate in unison with the driving element 19. Cam 22, as it rotates, will rock a bell 25 crank follower lever 23 and, through a link 24, oscillate arms 25 which have pin and slot connection with a card picker which is suitably mounted for vertical reciprocation. The downward movement of picker 26 will advance a card 30 C from the feed magazine 27 to the uppermost pair of feed rollers 28 which continue the downward movement of the card to further pairs of feed rollers 28. The several pairs of feed rollers are interconnected by gears generally designated 35 29 and are driven by a suitable gear secured to the shaft F so that the rollers 28 are in motion during the rotation of shaft F.

The record cards C (see Fig. 9) are placed in the magazine 27 so that the zero index point positions lead and the cards will pass the sensing station comprising individual sensing brushes 30 and common contact roller 31 in the order 0, 1, 2, 3 . . . 7, 8, 9. For each revolution of shaft F, a record card will be advanced from the hopper 40 to a position shown in Fig. 1 in which the card is in position with the brushes 30 about to sense the zero index point positions. During the second cycle of shaft F, the card is advanced to the punching station which comprises a plurality of 45 rows of punches 58 spaced in accordance with the arrangement of the index point positions on the record card. A gate 17 stops the leading edge of the card and holds the same in position until 50 punching has been effected. The gate 17 is connected by a link 78 to a bell crank cam follower 79 whose roller cooperates with a cam 80 secured to shaft F.

As the cards advance toward the sensing position, they will engage and rock a pivoted card 60 lever 32 which will cause closure of card lever contacts designated CLC.

Printing and punching mechanism

The printing and punching devices are operated from a shaft designated P upon which is freely mounted a gear 20a to which is secured clutch driving element 38. Cooperating with element 38 is a spring-pressed pawl 37 which is carried by a cam 62. Supported by and pivoted 65 to the cam 62 is an armature latch 36 which normally holds the pawl 37 out of engagement with driving element 38. Energization of clutch magnet 35 will cause the latch 36 to release pawl 37 for engagement with driving element 38 whereupon shaft P, to which cam 62 is secured, will

rotate. Secured to shaft P is a cam 39 which operates with a follower lever 40 whose upper extremity is connected through arm and link connection 53 to a shaft 54. Upon the shaft 54, at each end thereof is secured an arm 55a supporting a bail 55 which extends across the upper edges of a plurality of sliders 56. Sliders 56 are suitably mounted for vertical reciprocation and are normally urged upward by their springs 56a. The lower extremity of each slider carries a resiliently mounted interposer 57 which will pass the punches 58 in the related column in order. As the slider 56 moves upwardly, notches 59 will pass the nose of a pawl 60 in succession. During the upward movement of the slider, energization 10 of punch selecting magnet 61 will attract its armature 61a and release pawl 60 for engagement in one of the notches 59. The notch engaged will depend upon the time of operation of magnet 61. 20

After the sliders 56 have been positioned, punch plate 65, which is mounted for horizontal reciprocation, will be moved toward the left to force the positioned interposers 57 against the selected punches 58 and force the same through 25 the record card. The plate 65 has connected to it a link 64 whose other end is connected to a bell crank follower 63 which is operated by the cam 62 on shaft P.

Secured to the shaft 41 are arms 42 between 30 the extremities of which extends a bar 43. Bar 43 controls positioning of type carriers 44 which carry type elements 45 past printing position opposite platen 46. As the type carriers 44 move upwardly, notches 47 pass the nose of stopping 35 pawl 48 in succession. During such movement, energization of print selecting magnet 49 will attract its armature 49a to trip pawl 48 into engagement with one of the notches 47, the notch selected depending upon the time of energization 40 of magnet 49. As will be explained in connection with the circuit diagram, the punch selecting magnet 60 and the print selecting magnet 49 will be concurrently energized through parallel circuits and the digit punched will correspond to 45 the digit printed. Where nothing is to be punched in a card column, the punch slider moves to its extreme position with the interposer 57 advanced beyond the uppermost punch 58. Similarly, where a type bar 44 is not positioned 50 for printing a digit, the lowermost type element will advance beyond the printing position. For each type carrier there is provided a pivoted hammer 52 normally latched in the position shown by a latch 52a. Extending across the 55 latches is a bail 51 pivoted at 51a and having arm and link connection 50 to the arm 42 at a point on the arm between shaft 41 and rod 43. The proportion of the parts is such that as the arm 42 moves clockwise, bail 51 will move in the same 60 direction and near the extremity of the movement of arm 42, the bail will rock latches 52a clockwise to release the hammers 52.

Adding slide unit

In Fig. 1, the gear 20a, through an idler 81, drives a gear 82 which is freely mounted on shaft AS. Secured to gear 82 is clutch driving element 83 which, by virtue of the gear connection to the main drive shaft 10, is in constant rotation. Cooperating with element 83 is a spring-pressed pawl 84 which is pivoted to, and carried by, cam 78. The armature latch 85 normally holds the clutch disengaged. Energization of magnet 78 will release pawl 84 for engagement with the 75

driving element 83 and when so engaged, shaft AS will rotate. Connected to the pawl 84, through a curved link 86, is a dog 87 which lies in the path of armature latch 85 and when engaged by the latch will disengage the clutch, after it has made a half revolution.

Under certain conditions of operation, it is desired to have the shaft make a complete revolution, in which case the magnet 16 is held energized until the dog 87 has passed beyond the latching point of armature latch 85. Associated with the armature latch 85 is a pair of contacts 88 which close when the latch 85 is attracted by the magnet 16.

The cam 75 cooperates with a follower arm 74 secured to a shaft 73 upon which are secured arms 72 which have pin and notch connection with a bar 71 (see also Fig. 2). As the bar 71 moves toward the left (Fig. 2), adding slides 69 will follow under the influence of their springs 70. Each slide 69 is provided with a plurality of notches 68 which pass the toe of a pawl 67 in the order 0, 1, 2, 3 . . . 7, 8, 9 as the correspondingly numbered index point positions of the record card pass the sensing brushes 30. Latch 67 is normally held out of cooperation with the notches by armature latch 66a which releases the pawl 67 for engagement with the notches 68 upon energization of magnet 66. Carried by each slide 69 is a group of contact plungers 89 which are insulated from one another and from the slide. In line with the contact plungers 89 for each column there is a line of contact segments 90 over which the contacts 89 slide as the slide 69 reciprocates. If the record column sensed contains a perforation in the "0" position, the pawl 67 will be tripped to engage the "0" notch 68 and the contact 89 farthest to the right will be in position over the right hand "0" segment 90. If the column contained a perforation in the "1" position, the pawl 67 would engage the "1" notch 68 and the contact 89 farthest to the right would be in position over the right hand segment 90 designated "1." Thus, for any digit entered on the slide 69, the right hand contact 89 will take a position over the corresponding right hand segment 90.

Each group of segments 90 associated with a bar 69 is carried by an insulating member 91 which is mounted for horizontal movement and has an extending portion 92 provided with a notch in which the toe of the pawl 93 is normally in engagement, holding the member 91 in the position shown in Fig. 2 against the tension of its operating spring 94. A magnet 95, upon energization, will rock pawl 93 out of engagement with the notch in extension 92 so that spring 94 will move member 91 toward the right a distance equal to the space between two adjacent segments 90.

The magnet 95 is energized whenever a unit is to be carried into the related order, as will be explained in connection with the circuit diagram, and this displacement toward the right of member 91, in effect, causes an advance of one step by the slide 69 with respect to the member and its contacts 90. Abutting the end of extension 92 is the blade of a pair of contacts 95a which close when the member 91 moves toward the right. In line with slide 69 is a pair of contacts 96 which are normally held open by a lateral extension of the slide and which close when the slide has moved toward the left a distance equal to one and a half times the spacing between two adjacent segments 90; that is, when

the right hand contact 89 has moved to a position half way between the right hand segments 90 designated "0" and "1." Between the slide 69 and its companion slide 91 is a pivoted lever 97 whose upper arm is engaged by a pin 98 in slide 69 when the slide is restored toward the right to rock the lever clockwise and by engagement with the pin 99 in extension 92 will restore the member 91 to its latched position.

In Fig. 2a is shown a slide 69a which is positioned in exactly the same manner as the slide 69 of Fig. 2. This slide carries three contact plungers designated 89a and one designated 89b. The three contacts 89a are electrically connected to one another and are insulated from the single contact 89b. The contacts cooperate with a fixed member 91a of insulating material in which a single set of contact segments 90 is embedded. In restored position, the contact 89b occupies the position as shown and advances toward the left to engage the segments 90a in order as the correspondingly numbered index point positions of the card pass the sensing station. Sensing of a perforation in a related card column will interrupt the slide 69a with the contact 89b in position over the segment 90a corresponding to the value of the perforation.

The machine is provided with a number of slides 69 with cooperating members 91 and also a number of slides 69a with cooperating members 91a. The manner in which the units are grouped to form what will be termed an adding section will be more fully explained in connection with the circuit diagram.

35

Factor slides

When the machine is utilized to perform multiplying operations, the mechanism of Figs. 4 and 5 is brought into operation. This mechanism is driven from the factor slide shaft FS (Fig. 1). Loosely mounted on the shaft is a gear 100 which is driven from the gear 82 through an idler 101 which, as explained above, is driven through intermediate gearing to the constantly running shaft 10 so that the gear 100 is also in constant rotation. Secured to the gear is clutch driving element 102 with which spring-pressed pawl 103 carried by cam 104 cooperates. The pawl 103 is normally held out of engagement with the driving element 102 by the armature latch 105. Energization of magnet 106 will release pawl 103 and shaft FS will consequently rotate. Cooperating with cam 104 is a follower arm 107 secured to shaft 108 to which are secured arms 109 which have pin and notch connection with a bar 110 (see also Fig. 4). As the bar 110 moves toward the left, as viewed in Fig. 4, slides 111 will follow under the influence of their springs 112 and notches 113 will pass the toe of stopping pawl 114 as the correspondingly numbered index point positions of a record card pass the sensing brushes 30. The pawl 114 is normally latched out of cooperation with the notches 113 by armature latch 115 which is controlled by the magnet 116.

The magnets 116 are energized in response to the sensing of a multiplicand or a multiplier factor and control displacement of the slides 111 accordingly. Carried by the slides 111 which are positioned in accordance with the multiplier factor are eight contact plungers 117 (see Fig. 5) of which four are mounted on each side of the slide and the slides 111 associated with the multiplicand factor carry four contact plungers 117 of which two are located on each side of the 78

slide. The slides and contact plungers are designated with the suffixes MP and MC in the drawings to distinguish them as being associated with the multiplicand or multiplier. Each contact plunger 117MC and each contact plunger 117MP traverses a row of contact segments 118 and an entry of a digit in any slide 111 is represented by the positioning of its contact plungers 117 over the segments 118 corresponding to the digit entered. The circuit connections controlled through the contact devices 117, 118 will be more fully explained in connection with the circuit diagram.

15 Cam controlled contacts

In the machine are provided several cam operated contacts whose timing is designated in Figs. 7 and 8. Thus, contacts which are controlled by cams on the card feed shaft F are designated with the prefix F, those carried by shaft P are designated with the prefix P, and the cam contacts prefixed AS are on the shaft AS. Also carried by the shaft P is an emitter designated E1 (Fig. 18) which comprises a stationary commutator with ten contact segments 119 and a brush 120 carried by an arm secured to shaft P. Mounted on shaft AS (see also Figs. 18 and 19) are multiplying brushes 121 which cooperate with two sets of fixed contact segments 122 and 123. For each set of segments 122 and 123 there is a collector segment designated 122a and 123a respectively which are wired as shown on the circuit diagram.

As explained above, the shaft AS is driven 35 through a half-revolution clutch and during multiplying operations the shaft makes a half revolution for each record card so that the brushes 121 advance 180 degrees for each operation as will be explained.

40 Circuit diagram

The operation of the machine in which a plurality of amounts of a record card are cross added and the sum thereof punched back in the card 45 will first be described. In Fig. 9, the record card C has three fields designated C1, C2, and C3 in which perforations representing the amounts 679, 506, and 417 are punched. The amounts in these three fields are to be added together and 50 the sum punched back in field C4. Referring to Fig. 6, the sensing brushes which traverse the three amount fields C1, C2, and C3 are wired to plug sockets 124 and the punch selecting magnets 61 which control punching of the field C4 are 55 wired to plug sockets 125. The sockets 124 are connected through plug connections 126 to plug sockets 127 as indicated, with the units digits of the three amounts connected to three adjacent slide controlling magnets 66, the tens digits 60 connected to the next three lower magnets 66, and the hundreds digits to the following group of three slide controlling magnets 66.

Each set of three magnets 66 and associated mechanism constitutes what will hereinafter be 65 termed a section of the adding mechanism. Each section includes two slides 69 and a slide 69a arranged and wired together as shown in Fig. 6. Thus, for a machine having a capacity to add together three 3-place numbers, there will be 70 four sections and each section will have two slides 69 and one slide 69a. For greater capacity, additional slides 69 are included in each section and there will be only one slide 69a in any case.

The plug sockets 125 are connected through 75 plug connections 128 to sockets 129 which are

connected to the print controlling magnets 49 for operation of the print magnets concurrently with the punch magnets. From sockets 129 plug connections 130 extend to sockets 131 so that the magnets 49 and 61 which control the printing 5 and punching of the units digit of the sum are connected to the socket 131 associated with the units section of the adding mechanism. The magnets 49 and 61 which control the printing and punching of the tens digit of the sum are connected to the socket 131 associated with the tens section of the adding mechanism and so on. A group of sockets 200 is provided which is connected to contacts AS3. From these sockets connections 201 are made to sockets 127 of magnets 15 66 which are not connected to sensing brushes and which are associated with an overflow adding section. Contacts AS3 are timed (Fig. 7) to complete circuits to stop the connected slides in "0" position as will be explained. 20

With the plug connections made as indicated and with cards placed in the supply magazine 27, the machine is ready to commence operation. As a preliminary, the "Add" key is operated to open a pair of contacts 132 (bottom of Fig. 6a) 25 to deenergize relay magnet T if the relay is in energized condition due to possible previous multiplying operations during which the relay may have been energized, as will be explained. Thus, at the start, relay magnet T is deenergized and 30 its several contacts T1—T7 are in the positions shown on the diagram.

Depression of the start key 11 will close contacts 12 to complete a circuit from negative side 35 of line 13 through contacts 12, motor control relay R to left side of the line 14. Relay R will close its contacts R2 establishing a holding circuit through the cam contacts P-2 and will also close its contacts R1 to complete the circuit through the motor M. This places the shaft 40 10 of Fig. 1 in operation. Operation of start key 11 will also close a pair of contacts 15 which complete a circuit from line 13, contacts 15, card feed clutch magnet 16, to line 14. Energization of magnet 16 will couple the card feed shaft F 45 for rotation and this shaft will now turn to cause advance of the first card from the supply magazine. The cycle thus initiated is an idle cycle, required to advance the first card into the machine. 50

The contacts 12 are held closed until the first card has advanced far enough to cause closure of card lever contacts CLC which takes place at about the "12" time in this preliminary cycle (see Fig. 7) and at which time a further holding circuit for the motor control relay R is completed through the stop key contacts 34 and the card lever contacts CLC. During this cycle, the F cams operate and toward the end of the cycle, contacts F1 close after contacts CLC have closed, to complete a circuit from line 13, contacts CLC, wire 33, contacts F1, relay contacts T4, print clutch magnet 35, to line 14. The shaft P is now coupled for operation and will make one cycle, which is an idle cycle, at this time, since no card 55 is in position to be punched and no entries as yet have been made in the adding mechanism. The first card at this time is in the position indicated in Fig. 1 with the "0" index point positions ready to pass the sensing brushes. Near the middle of 60 the revolution of the shaft P, contacts P3 close, completing a circuit from line 13, contacts CLC, wire 33, contacts P3, contacts T6, through the adding slide clutch magnet 76 to line 14. As explained, energization of clutch 76 will cause clo- 70 75

sure of contacts 88 which will provide a holding circuit from line 14, through magnet 76, contacts T8, contacts 88, cam contacts F4, wire 33, contacts CLC to line 13. This circuit will be maintained until the dog 87 (Fig. 1) has passed the half revolution declutching position so that the shaft AS will make a complete revolution, first restoring the slides during the first half revolution of shaft AS which is concurrent with the second half revolution of shaft P.

Near the end of the print cycle, cam contacts P1 close, energizing the feed clutch magnet 16 and shaft F enters upon another cycle of operations to advance the card past the sensing brushes 30. This cycle of shaft F is exactly the same as the preliminary idle cycle except that the card lever contacts CLC are now closed throughout the period indicated in shaded outline in Fig. 7 to about the "5" time in the cycle. Just at this time, contacts F2 close to bridge, the contacts CLC which, if a second card follows, again close at about "12." Thus, during the second card feed cycle (the first effective cycle) current is supplied throughout the entire cycle from line 13 (Fig. 6a) to wire 33 through either contacts CLC or F2 and this connection will continue as long as cards continue to feed in succession, past the sensing brushes. During this passage of the card by the brushes 30, the adding slides are moved in synchronism with the card, this movement taking place during the second half of the revolution of the shaft AS. After the slides have taken a position under control of the perforations sensed they will remain in setup position while the card feed shaft completes its cycle, during which it advances the card into punching position. At this point, the slides are differentially positioned in accordance with the amounts sensed in the fields C1, C2, and C3 of the card C. A representative entering circuit may be traced as follows: from line 13 (Fig. 6a), contacts CLC or F2, wire 33, circuit breaker contacts F3, wire 133 (Fig. 6), common contact roll 31, perforation in the record card, corresponding brush 30, plug socket 124, plug connection 126, socket 127, slide positioning magnet 66, wire 134, to line 14. The circuits through the magnets 66 will, of course, be completed at differential times in accordance with the location of the perforations in the card columns and the movement of the slides 69 and 69a toward the left will be interrupted at differential times accordingly.

In the overflow adding section circuits are completed from line 13, contacts CLC or F2, wire 33, contacts AS3, sockets 200, connections 201, sockets 127, magnets 66, wire 134 (Fig. 6) to line 14 to stop the overflow slides 69 in zero position. The overflow adding section is identical in construction with the other sections. It is necessary in positions where no entry is made directly from the card to stop all slides at "0" for which purpose contacts AS3 are provided to complete the circuits traced, at the proper time to set all unused slides in zero position.

65 *Tens carry circuits*

Provision is made for carrying from the units section of the adding mechanism to the tens section, from the tens section to the hundreds section, and so on, whenever the sum of the digits entered into any one section aggregates 10 or more. In the units section (Fig. 6) the carry magnets 95 are omitted since no carrying is effected into this section. For each of the sections higher than the units, there is provided a relay

magnet A which, through circuits to be traced in more detail hereinafter, will be energized whenever the sum of the digits entered in the next lower order aggregates 10 or a multiple of 10. The circuit for energizing relay A extends to wire 5 135 from line 14, through series circuits which will be traced later, thence through relay A, through its contacts A1, the upper carry magnet 95 to wire 136 (Fig. 6a), contacts P5, wire 33, contacts CLC or F2, to line 13. Energization of carry 10 magnet 95 will release the related slide 91 for movement toward the right and, in effect, adding one unit to the setting thereof. Relay magnet A is adjusted to open its contacts A1 to break the circuit to magnet 95 after it has been energized, 15 but before the contacts 95a operated by the related slide close. Opening of contacts A1 is accompanied by closure of contacts A2 which set up a holding circuit from wire 135 through relay magnet A, contacts A2, wire 136, to line 13, as 20 before. This circuit, as will be explained later, is held momentarily as the slides of the section pass through 10 and the circuit is broken when 10 has been passed so that contacts A1 again close and contacts A2 open.

If the slides in their continued advance now aggregate 20, a circuit is again established between line 14 and wire 135 energizing magnet A a second time and continuing the circuit through contacts A1, contacts 95a, which were closed previously, and the second carry magnet 95 to cause shifting of the next slide 91 one step toward the right. Thus each slide 91, as it is shifted to receive a carry movement, closes its contacts 95a to prepare the next slide to receive the next carry 35 impulse, if one is forthcoming. The specific manner in which the carry circuit to magnet A is completed is best explained by considering several specific problems. This will now be done in connection with Figs. 11 to 17.

Referring first to Fig. 10, the interconnecting wiring between the several orders of a section will first be explained. The three contact plungers 89a are connected through a wire 137 to contact points B1 and through these contacts to line 14. The other contact plunger 89b on the slide 69a is connected through a wire 138 and normally closed contacts B2 to line 14. The contact segments 90a are connected through flexible wires 139 to the contact plungers 89 of the next slide 69, the connections being made in the order shown. The segments 90 of the intermediate order are connected through wires 140 to the contact plungers 89 of the lowermost slide 69. Through the wires 140, the like-numbered segments 90 are both connected to the same contact plunger 89. Finally, the segments 90 of the last order are connected to a group of wires 141 which, through the contacts D1 of the multi-contact relay D, may be connected to the lines 142 extending to contact segments 119 of the emitter E1. The "0" wire 141 has a lead 143 extending to the two contacts 96 in parallel as shown. With the machine at rest, the slides, the contacts, and the circuit connections are in 60 65 the relationship shown in Figs. 6 and 6a.

As the card traverses the sensing brushes, the slides 69 move in synchronism therewith. In Fig. 11 is shown, the relative positions of the parts when the "5" index point position of the card has reached the brushes 30 and it is assumed that the column connected to the lowermost slide 69 contains a zero so that this slide was stopped at zero while the other two continued their advance. At the "5" position, the

aggregate amount standing on the three slides is 10 and it is at this point, as the two uppermost slides pass through the "5" position, that a carry circuit is completed to the next higher order section of the adding mechanism. The circuit which is completed at this instant is accented in heavy dotted lines in Fig. 11 and is traceable as follows: from line 14 to contacts B2, wire 138, contact 89b, the "5" segment 90a, wire 139 running from the "5" segment 90a to the fifth contact 89 from the left of the second slide 69 through "0" segment 90 of the central slide, the connected wire 140 to the right hand contact 89 on the lowermost slide, thence through the "0" segment 90 of this slide, the "0" wire 141, the lead 143, the upper contact 96, which is closed due to the advance of its slide beyond "0" position, wire 135, and thence through relay A and carry magnet 95 of the next higher order to wire 136 and line 13, as explained above.

In Fig. 12 is shown the path through which a carry circuit is completed when all three slides 69 are passing through the "4" position without having been interrupted. At this point the carry circuit is completed as again emphasized by a heavy dotted line with the circuit extending from line 14, contacts B1, wire 137, the central contact 89a on slide 69, and thence in series through the indicated wires 139, 140 and lead 143 through the contacts 96 and wire 135 to the relay A. If the three slides should be interrupted at this point, the circuit will continue to hold relay magnet A energized through the holding circuit extending from wire 135, relay magnet A, contacts A2, wire 136, thus holding contacts A1 open so that only the single carry operation can be effected.

As the slides 69 continue uninterruptedly from the position in Fig. 12 to that in Figs. 13 and 14 in succession, that is, as they all pass through the "5" and "6" positions, there will be no further carry circuits completed. As the slides reach the position of Fig. 15 where all three are at "7," a second carry circuit is immediately completed, this circuit being indicated by the heavy dotted line and is traceable from line 14, through contact B1, wire 137, the left hand contact 89a, the "6" segment 90a, wires 139 and 140, as indicated, lead 143, contacts 96, wire 135, relay A, contacts A1, the first pair of contacts 95a, which were closed as a result of the first carry, and thence to the second carry magnet 95 and wire 136 to line 13. The magnet 95 causes shifting of another slide 61 of the next higher order adding section, contacts A1 again breaking before the second pair of contacts 95a close so that only the one magnet 95 is energized.

In Fig. 16 is shown the circuit path for completion of a second carry at the time the positions of the three slides represent 20. In this position, the upper slides have been stopped at "6" while the lowermost slide is at the "8" position, either stopped there or passing through. The circuit is emphasized and it is quite apparent without detailed tracing of the same.

In Fig. 17 is shown the path through which the carry circuit is completed where the section has already received a carry impulse and this added "one" combined with the setting of the bars aggregates 10. Thus, in Fig. 17, the lowermost slide is stopped at "0"; the central slide has stopped at "4," but its companion slide 61 has been moved one step toward the right so that, in effect, there is a "5" in the central slide; and

the uppermost slide is stopped at or passing through the "5" position. Here, again, the carry circuit is emphasized and extends through the contact 89b, the series connections through wires 139, 140, and 141 to lead 143 and the upper contacts 96 to the wire 135 and the appropriate carry magnet 95 of the next higher order.

It is thus seen that the carry circuit may follow through various circuit paths depending on the relative positions of the slides and the circuit may go through contact 89b or one of the contacts 89a. Whenever the aggregate setting of the slides is exactly 10, the circuit will go through contact 89b. In certain cases, for example, that shown in Fig. 12, where the three bars advance together, they move from a position in which they aggregate 9 when all three are set at "3" to a position where they all aggregate 12 where all bars are set at "4" and no carry circuit is completed until they are all at the "12" position. If one of these slides had been stopped at the "2" position, then when the other two arrived at "4," the aggregate would have been exactly 10 and the carry circuit traceable through contact 89b. These carry operations all take place as the card moves past the sensing station and at the end of the card feed cycle, each section of the adding mechanism will be in readiness to have the total read out immediately. At the end of the card feed cycle, the slides will be in their forward position with the setting where they will remain until they are restored in the second half of the following printing and punching cycle.

Total printing and punching

35

Near the end of the card feed cycle, cam contacts F1 close, again energizing the print clutch magnet 35 so that a revolution of shaft P is initiated. Cam contacts P4 close just as the cycle commences and cause energization of relay magnet B through a circuit from line 14, relay magnet B (Fig. 6a), contacts P4, wire 33, contacts CLC, to line 13. The magnet B remains energized throughout the print and punch selecting portion of the cycle and, during such period, it holds open its contacts B1 and B2, the former cutting off the carry circuit connections to the contacts 89a, and the latter opening the carry connection to contacts 89b which are now connected to the plug socket 131 through closure of contacts B3. At the same time, contacts P5, controlled by the same cam as contact P4, open the common carry line 136. In parallel with relay B are a plurality of relay magnets D, each of which controls a group of contacts D1 (see also Fig. 10) which are placed in the wires 141. These contacts are open during entering operations to prevent possible back circuits and are closed to connect the wires 141 to the wires 142 so that the total may be read out. As emitter brush 120 rotates with shaft P, it contacts the segments 119 in succession in the order 0, 1, 2, 3 . . . 7, 8, 9 in synchronism with the movement of the type elements 45 past the printing position in the same order and in synchronism with the movement of the punch interposers 67 past the punches 58 in the same order. Thus, each of the wires 142 will be connected in turn to wire 33 and through contacts CLC to line 13. The readout circuits may best be explained by tracing several specific examples.

In Fig. 10, the slides of the units section are shown as being set to represent the three digits "3," "3," and "1" whose sum is "7." When the brush 120 arrives at the "7" segment 119, a cir-

cuit will be completed from line 13 to brush 120 as traced, "7" segment 119, the "7" wire 142, the "7" wire 141 including the appropriate contacts D1, the "7" segment 90 of the lowermost member 91 and thence serially through the heavy line circuit to the contact 89b, thence through wire 138, contacts B3, now closed, to plug socket 131. From here the circuit is traceable in Fig. 6 through plug connection 130 to plug socket 129 and plug connection 128 to plug socket 125. From the sockets the branch circuits extend through print magnet 49 and punch magnet 61 and thence to line 14.

In the tens order section of Fig. 10, the three slides are positioned to represent 8, 9, and 2 respectively whose aggregate amount is 19. The "1" has, of course, been previously carried to the next higher order so that the "9" is to be read out of this tens section. This circuit is completed when the brush 120 reaches the "9" segment 119 and is traceable on the drawings through the heavy line circuit path shown. Further examples are shown in Fig. 11 where the circuit is completed at the "0" time through the same circuit path 140, 139 through which the carry impulse 25 had been previously completed.

In Fig. 12, the printing circuit is shown in heavy full lines together with the carry circuit in heavy dotted lines. The print circuit will be completed at the "2" time through the "2" segment in the 30 lowermost slide 91.

Fig. 13 shows in heavy lines the path of the print circuit which is completed at the "5" time, and Fig. 14 shows in heavy lines the path of the circuit completed at the "8" time.

After the brush 120 has traversed all the segments 119, the slides are restored while the printing hammers are tripped and the punches are forced through the card. Near the end of the cycle, contacts P1 close to cause advance of the 40 new card past the sensing brushes and set up a new set of digits on the adding slides.

A complete cross addition is thus obtained of a plurality of amounts in the several fields of the record card which are concurrently sensed and 45 concurrently entered into the adding mechanism of the machine during the feeding cycle with the tens carry operations taking place immediately when the sum of the digits in any section is 10 or greater. During a second cycle, the total of 50 all the amounts is immediately read out without movement of any of the mechanism of the adding sections.

Multiplying mechanism

The machine is arranged to read two amounts 55 representing a multiplicand and multiplier respectively and enter these into multiplying mechanism which will derive the various partial products of the result and will enter the partial products into the adding slides which, in turn, will add the 60 partial products together and punch the result back in the record card.

When the machine is used for multiplying, the plug connections 126 (Fig. 6) are removed from the sockets 127 and other plug connections are 65 made which are designated 145 (Figs. 6 and 6a). The jacks at the ends of these connections are inserted in the sockets 127 beside which they are shown. The other ends of the connections 145 extend to plug sockets 146 (Fig. 6c) from where 70 flexible wires 147 extend to the contact slide plungers 117MC, as indicated. Adjacent to the sockets 146 are indications U, T, H, and TH and the connections from these sockets are made to the units, tens, hundreds, or thousands sections 75 of the adding mechanism in accordance with the

adjacent designation. Further plug connections 148 (Figs. 6 and 6b) are made to the brush sockets 124 whose brushes traverse the multiplier field of the card. These connections extend to the factor slide controlling magnets 116MP. Similar plug 5 connections 149 are made to the brushes 124 traversing the multiplicand field of the card and the factor slide magnets 116MC (Figs. 6, 6a, and 6c). Overflow positions are connected to sockets 200 as for adding operations.

With these connections made and cards placed in the magazine, the machine is ready to start. It is first necessary to depress the multiplying key 150 (Fig. 6a) to close contacts 151 and thereby energize relay magnet T which, through closure of its contacts T1 will set up a holding circuit from line 14, magnet T, contacts T1, the "add" contacts 132, to line 13. The relay magnet T will also shift its contacts T2, to T1 and they will remain in shifted position throughout multiplying operations until either contacts 132 are opened or the main line circuit is broken by opening of the main switch. Switch 88a is opened for multiplying operations to prevent contacts 88 from energizing the adding slide magnet 76 during such operations. A key 203 is provided which is depressed to close contacts 204 and energize magnet 76. This is for the purpose of changing the phase relationship of the slides as will be explained.

Depression of the start key 11 at this time will close contacts 12, energizing the motor control relay R as for adding operations, which, through its contacts R1, will close the circuit through motor M. The accompanying closure of contacts 15 will energize the card feeding clutch magnet 16 and, as explained, the card will be fed from the supply magazine to a position where the "0" index point positions are about to pass the sensing station.

It will be noted in Fig. 1 that the engaging edge of clutch element 19 is 180° in advance of the engaging edge of element 83 so that if key 11 is operated with the parts in the position of Fig. 1, feed clutch magnet 16 will be energized and the 45 feed shaft F will rotate for one revolution. At 180° shaft AS will commence to turn due to prior energization of magnet 76 by means of key 203 and make a half revolution so that at the end of the first feed cycle the adding slide will be in re- 50 stored position.

Near the end of the card feed cycle (see Fig. 8), cam contacts F1 close, completing a circuit from line 13, card lever contacts CLC, which are now closed, wire 33, contacts F1, contacts T1, the add slide clutch magnet 76, to line 14. The adding slides 69 and 69a will move toward the left, which is the direction for receiving entries and the shaft AS will be declutched after a half revolution since contacts 88 are now not in circuit 60 with magnet 76, leaving the slides in setup position. Before shaft AS comes to rest, contacts AS1 close, completing a circuit from wire 33, contacts AS1, contacts T5, print clutch magnet 35, to line 14. The print shaft P now after its element 38 has turned 180°, makes a cycle during which the type bars and punch bars move to position and during this cycle contacts P3 and P3a close. Contacts P3 complete a circuit through contacts T2 to energize the factor slide magnet 70 106 and at the same time contacts P3a energize adding slide magnet 76 through contacts T3. Both sets of slides will consequently be restored during the second half of the print cycle. The shaft AS will make a half revolution and stop 75

with the slides in restored position, while the shaft FS will continue on through the first half of the next card feed cycle which is initiated by closure of contacts F1.

- 5 The two cycles of operation following the first card feed cycle are, of course, idle operations since there have not yet been any entries made in the machine and the first card is still in the position about to pass the brushes. With the 10 occurrence of the second feed cycle, this first card will advance to pass the sensing brushes 30 and as it does so, entering circuits will be completed to energize the magnets 116MP (Fig. 6b) and magnets 116MC (Fig. 6c) at differential 15 times according to the location of the perforations in the MC and MP fields of the record card. A representative entering circuit may be traced from line 13 (Fig. 6a), contacts CLC, wire 33, cam contacts F3, wire 133, common contact roll 31, 20 brush 124 in the MP field, for example, plug connection 148 (Fig. 6b), magnet 116MP, lead 152 which connects with wire 134 (Fig. 6) and line 14. Energization of the magnet 116MP takes place as the factor slides 111 (Fig. 4) move toward the left and take position according to the 25 perforations sensed. At the end of the feed cycle, the first card is in punching position and the factors are set up on the factor slides.

During the following cycle, the partial products 30 of the two factors entered will be automatically determined and entered upon the adding slides as the latter now move in setting up direction. Closure of contacts F1 at the end of the feed cycle will have energized the adding slide magnet 16, freeing it to make a half revolution. During this half revolution, the commutator brushes 121 of Fig. 18 also make a half revolution and during their movement, circuits will be completed to enter all of the partial products obtained 40 through circuits which will now be set forth in connection with Figs. 6b, 6c, and 21.

An explanation of the circuits may best be had by a consideration of a specific problem. Let us take, for example, the multiplying problem set 45 forth in Fig. 20 in which the multiplicand 87 is to be multiplied by 96. In Fig. 20, the several partial products 42, 48, 63, and 72 are indicated and, when added together with proper denominational allocation, give the product 8,352. During the half cycle of shaft AS, the units digit 2 will be entered on the units section of the adding slides, the digits 4, 8, and 3 will be entered into the tens section, the 4, 6, and 2 into the hundreds section, and the digit 7 into the thousands section. In Fig. 6b, the units multiplier contact plungers 111MP are advanced to engage the group of segments 118 in the "6" position and the tens group of plungers 111MP is advanced to engage the group of segments 118 in the "9" position. In 55 Fig. 6c, the slide contacts 111MC are advanced to engage the segments 118 in the "7" position and the contacts 111MC in the tens position are advanced into cooperation with the segments 118 in the "8" position.

60 The segments, commutators, and circuit connections involved in the consideration of the problem of Fig. 20 are shown more clearly in Fig. 21, which includes only the pertinent circuits. The circuits which are involved in Fig. 70 21 are shown in heavy lines on Figs. 6b and 6c. As the adding slides 69, 69a move toward the left to take positions 0, 1, 2, 3, etc., in succession, the brushes 121 rotate in synchronism therewith to successively contact the segments 122 in the same 75 order. When the brushes have reached the "2"

position, a circuit will be traceable from line 13 (Fig. 6a), contacts CLC, wire 33, contacts P5, wire 136 (Figs. 6 and 6b), cam contacts AS2 (see also Fig. 21), wire 153, the units group of contacts 117MP, wire 154, to the "2" segment 123 5 of the "7" multiplying commutator, to brush 121, and from the brush 121 to its associated collector ring 123a, to wire 155, segment 118, associated contact 117MC, wire 147, whose socket 146 is plug connected to the slide magnet 66 in the 10 units section of the adding mechanism, thence through wire 134 to line 14.

At the same instant, a similarly traceable circuit is completed through the "2" segment of the No. 8 commutator associated with the tens 15 slide which will energize a magnet 66 in the hundreds section of the adding mechanism. As the commutator brushes advance, a similar circuit is traceable through the "3" segment 122 of the No. 7 commutator in the tens order to energize a 20 magnet 66 in the tens section of the adding mechanism. Similarly, and in turn, a magnet 66 in the hundreds section will be energized to enter a "6," then the magnet 66 in the thousands section will be energized to receive a "7" and 25 a third magnet in the tens sections will be energized to receive an "8."

Thus, during the half revolution of the commutator brushes, all the possible digits occurring 30 in the several partial products are concurrently entered into appropriate positions in the adding mechanism. From this point on, the operation is the same as for straight adding problems where the digits are set up directly on the slides 35 under control of the card.

Briefly, the sum of the partial products is read 40 out of the adding slides as the type bars rise during the first half of the ensuing print cycle. During the sec'd half of the cycle the adding and factor slides are restored.

At the end of multiplying operations, the shaft 45 AS will be in "restored" position and if the machine is now to be used for adding operations, it is necessary to turn shaft AS a half revolution to establish the proper relationship for adding operations. This is effected by closing contacts 204 to energize slide magnet 16 before start key 11 is operated again so that during the initial card feeding cycle the add slides will move in setting up direction in correct synchronization. 50

An indicator (not shown) may be carried by the visible extremity of shaft AS which by its position will tell whether the slides are in advanced or restored position so that the operator before operating the machine can readily tell 55 whether the parts are in proper synchronous relationship.

While there has been shown and described and 60 pointed out the fundamental novel features of the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following claims.

What is claimed is as follows:

1. In a calculating machine, a plurality of differentially positionable entry receiving devices, operating means therefor, controlling means for said operating means for causing positioning of each device to represent any digit, contact means for each entry receiving device, each contact means settable by its related receiving device in 75

accordance with the digit entered therein, a recording element, a control magnet therefor, an emitter for transmitting a series of electrical impulses, one for each of the digits, means jointly controlled by all of said contact means for selecting from said series of electrical impulses the impulse corresponding to the units digit of the sum of the digits set up, and a circuit connection including the control magnet, the emitter and the 10 selecting means, said selected impulses causing energization of said magnet through said connection to control the operation of the recording element in accordance with the selected impulse.

2. In a record card controlled machine, means for sensing a record card for a plurality of digits, a plurality of differentially positionable entry receiving devices, each controlled by said sensing means to receive one of the digits sensed, electrical circuit connections adjusted under control 20 of said devices and arranged in accordance with the table of addition, a recording element, controlling means therefor and means including said circuit connections controlled in accordance with the relative displacement of said devices for causing an operation of said controlling means to cause said recording element to be positioned to record the units digit of the sum of the digits sensed.

3. In a machine of the class described, an entry receiving device comprising a plurality of elements each positionable to represent any digit, a readout device comprising a plurality of sets of contact making devices adjusted by said positionable elements, there being a separate set of 30 contact making devices for each element, circuit connections interconnecting said sets of contact making devices and arranged in accordance with the table of addition whereby a different continuous circuit connection will be established through all the sets of contact making devices for each of the digits, representing the units digit of the sum of the digits entered in the entry receiving device, means for emitting a series of 40 timed impulses, representative of the several digits, a recording control magnet included in each possible continuous circuit connection, and means controlled by said sets of contact making devices, through the said continuous circuit connection for selecting the impulse corresponding 50 to the said units digit of the said sum for energizing said magnet.

4. In an adding machine, a plurality of groups of denominational ordered elements, each element being differentially settable to represent any digit, means for causing the elements of one group to be set to represent the units digits of a number of multidenominational amounts, and for causing the elements of another group to be set to represent the tens digits of said 55 amounts, a set of contact making means for each element, each set being adjusted by its element in accordance with the digit represented on the element, circuit connections for each group for connecting the contact making means thereof in series, the connections for each group being arranged to effect a completed connection extending through all the elements of the group representing the units digit of the sum of the digits entered in the related group, tens carrying means controlled by the group of elements in which the units digits are entered, and effective when the sum of the units digits is greater than 9, for causing the higher order group of elements to 70 represent an additional unit, recording means 75

and means including said completed connections, for controlling the operation of said recording means.

5. An adding mechanism comprising a set of units slides, a set of tens slides, means for differentially moving the slides of each set to represent digits therein, a readout device for each set controlled by the relative positioning of the slides in a set for reading out the units digit of the amount representing the sum of the digits on the 10 slides of the set, said readout device comprising contact making means adjusted by said slides and arranged in accordance with the table of addition and means including a part of the readout device of the units set for causing the readout device of 15 the tens set to read out one digit higher than the units digit of the sum of its digits when the units digit of the sum of the digits in the units set is more than nine.

6. In a record card controlled adding machine, 20 a set of units elements, a set of tens elements, means for sensing a record card for representations of multidenominational amounts, means controlled by said sensing means for entering the units digits of said amounts on said units elements, and the tens digits on said tens elements, each digit being entered in a separate element, a readout device for the set of units elements, a readout device for the set of tens elements, said readout devices comprising contact making means 25 adjusted by said elements and arranged in accordance with the table of addition, a carry mechanism between the said sets, and recording means controlled in part by said units readout device to record the units digit of the sum of said amounts, 30 and in part by the tens readout device to record the tens digit of the sum of the amounts.

7. In a record card controlled adding machine, a set of units elements, a set of tens elements, means for sensing a record card for representations of multidenominational amounts, means controlled by said sensing means for concurrently entering the units digits of said amounts on said units elements, and the tens digits on said tens elements, each digit being entered in a separate 40 element, a readout device for the set of units elements, a readout device for the set of tens elements, said readout devices comprising contact making means adjusted by said elements and arranged in accordance with the table of addition, 45 carrying mechanism between the said sets, and recording means controlled in part by said units readout device to record the units digit of the sum of said amounts and in part by the tens readout device to record the tens digit of the sum of the 50 amounts.

8. In an adding machine, a plurality of denominational ordered sets of slides each of which is provided with circuit closing means, the slides of each set having ten differential positions representative of the ten digits, means for adjusting the slides each to any digit representing position to represent a digit in each, a group of circuit connections for each set of slides arranged in accordance with the table of addition and interconnected under control of the related slides through said circuit closing means to represent by their interconnection the units digit of the sum of the digits represented on the related set of slides, means associated with each group of circuit connections for readjusting the same to represent a unit higher than said units digit of the sum, operating means for each readjusting means, and means including said circuit connections of each set of slides and operative when the aggregate 70 75

value of the digits represented in the related set is ten for rendering the said operating means of the next higher order effective.

9. The invention set forth in claim 8 in which 5 each group of circuit connections includes a plurality of normally stationary contact blocks which cooperate with the circuit closing means of the slides, said blocks being supported in a movable member, which member constitutes the means for 10 readjusting the circuit connections and in which the operating means for said member comprises mechanism for shifting the member to effect relative movement between the blocks and the circuit closing means.

- 15 10. The invention set forth in claim 8 in which

each group of circuit connections has associated therewith a plurality of readjusting means and an operating means for each; in which the means for rendering the operating means effective is operative when the aggregate value of the digits represented in the related set is ten and for each multiple of ten and means is provided to render the plurality of operating means responsive to said rendering means in succession whereby a different operating means is controlled for each multiple of ten and whereby the next higher order group of circuit connections will represent a unit higher for each said multiple represented in the lower order. 5 10

TORKEL E. TORKELSON. 15
